UNITED STATES PATENT OFFICE.

ALEXANDER GLOWICKI, OF CINCINNATI, OHIO.

DESIGN FOR A MOTOR-CASING.

58,222.

Specification for Design. Patented June 28, 1921.

Application filed October 13, 1919. Serial No. 330,495. Term of patent 14 years.

To all whom it may concern:

Be it known that I, ALEXANDER GLOWICKI, a citizen of the United States, and residing at Cincinnati, in the county of Hamilton and State of Ohio, have invented a new and ornamental Design for a Motor-Casing, of which the following is a specification, reference being had to the accompanying drawing, forming a part hereof.

The figure is a side elevation of an electric motor frame, showing my new design.

The dominating feature of the design consists in the oval or ellipsoidal shape motor frame, comprising the central motor field

frame portion and the duplicate bearing and cover sections secured to the opposite sides of the field frame.

I claim:

The ornamental design for a motor casing, as shown and described.

In witness whereof, I hereunto subscribe my name, as attested by the two subscribing witnesses.

ALEXANDER GLOWICKI.

Witnesses:

L. BECK,

M. BARRON.
